UNITED STATES PATENT OFFICE.

NORBERT CEIPEK, OF VIENNA, AUSTRIA-HUNGARY.

SAFETY EXPLOSIVE.

1,033,537.

Specification of Letters Patent. Patented July 23, 1912.

No Drawing.

Application filed September 5, 1911. Serial No. 647,741.

To all whom it may concern:

Be it known that I, NORBERT CEIPEK, a subject of the Emperor of Austria-Hungary, residing at Vienna, Austria-Hungary, have invented certain new and useful Improvements in the Manufacture of Safety Explosives, of which the following is a specification.

As is generally well known, many of the so-called safety explosives consist of a mixture of ammonium nitrate and a carboniferous agent. Experiments have shown that by adding to the above named mixture of ammonium nitrate and a carboniferous agent the powder of nitrated turmeric root, or by using the powder of nitrated turmeric root as the sole carboniferous agent mixed with the ammonium nitrate, the safety of working, the permanence and the explosive power of such explosive compounds are increased whereas at the same time their hygroscopic qualities are diminished.

The nitration of the powder of turmeric root is preferably performed in the following manner: The primary material, from which it is advantageous to extract previously the coloring substances by boiling in water, is dried and ground, whereupon it is treated with a mixture of nitric acid and sulfuric acid. The nitrating acid is a mixture of nitric acid, sulfuric acid and water in about the following proportions: 33% of nitric acid, 45.5% of sulfuric acid, 21.5% of water, and this mixture is generally used in the proportions of 10 parts by weight of the mixture to 1 part of weight of the treated dry material. The finely ground, dried and sifted material is added in successive small quantities into the nitrating acids and is constantly stirred until it is thoroughly and uniformly mixed with the acid. When the whole quantity of the treated material has been introduced into the acids an equal quantity of cold water is added, whereupon the stirring is interrupted and the whole mixture is left to rest until a powder of light yellow color has been precipitated on the bottom of the receptacle. After the reaction has taken place the acid is drained off, the product of the reaction is washed in water and dried. In this manner a product is obtained that is insensitive against blows or shocks. As primary material can also be employed carbonized turmeric powder which is submitted to the process of nitration.

The manufacture of the explosive is simple and without danger. From 80 to 90 parts of ammonium nitrate and from 20 to 10 parts of nitrated turmeric powder are 60 first carefully dried and then intimately mixed and finely ground in a drum mill. The explosive thus obtained is quite insensitive to shock, blow and free fire, and can only be exploded by an initial explosion, 65 preferably a detonator containing a charge of 2 grams.

If it is intended to mix with the ammonium nitrate besides the powder of nitrated turmeric root also other carboniferous 70 agents, it is preferable to use a mixture of carbonized turmeric powder and of carbonized sandal wood as a carboniferous agent because the admixture of the carbonized sandal wood considerably increases the speed 75 of combustion.

An explosive compound obtained by the intimate mixing together of 88% of ammonium nitrate, 1.05% of carbonized turmeric powder, 0.95% of carbonized sandal wood 80 and 10% of nitrated turmeric powder possesses an explosive power which produces an expansion of from 1300 to 1400 cm³ of Trauzl's lead cylinder and besides it presents full security of working and full permanence as also little hygroscopicity. For increasing the explosive power of the product to the said compound consisting of ammonium nitrate and nitrated turmeric powder may be admixed in the known manner 85 trinitrotoluene or dinitrotoluene or a mixture of these two nitro-compounds.

In order to obtain not only an increase of the explosive power of the said explosive compound but also an increase of their permanence and of their charging density and at the same time to diminish their hygroscopic qualities, to the said mixtures gelatinized nitro-cellulose may be added in accordance with the present invention.

As suitable proportions by weight for the constituents of an explosive made according to the invention, the following may be named: 82 parts of ammonium nitrate, 4 parts of nitrated turmeric powder, 10 parts of trinitrotoluene and 4 parts of a gelatin consisting of 0.17 parts of nitro-cellulose and 3.83 parts of dinitrotoluene.

The advantages of the use of nitrated turmeric root as the sole carbonaceous material in safety explosives reside in the facts that the explosives yield an extremely favorable

after-damp, that they have high stability when stored, and that in consequence of its fine subdivision and combustibility the nitrated turmeric powder develops high explosive power.

I claim—

1. A safety explosive which has great safety in use, great stability and high explosive power, comprising ammonium nitrate 10 mixed with nitrated turmeric powder as a carbonaceous material.
2. A safety explosive compound comprising ammonium nitrate mixed with nitrated turmeric powder and with another carbonaceous agent.

3. A safety explosive compound comprising ammonium nitrate mixed with nitrated and carbonized turmeric powder and with another carboniferous agent.

4. A safety explosive of the character described, comprising from 80 to 90 parts by weight of ammonium nitrate and from 20 to 10 parts of nitrated turmeric powder.

In testimony whereof I have hereunto set my hand in presence of two subscribing witnesses.

NORBERT CEIPEK.

Witnesses:

JOSEF RUBASCH,
AUGUST FUGGER.
